(57) **CLAIM**

The ornamental design for an automobile wheel face, as shown and described.

DESCRIPTION

FIG. 1 is a left perspective view of an automobile wheel face showing my new design;

FIG. 2 is a right perspective view thereof;

FIG. 3 is a front elevation view thereof; and,

FIG. 4 is a side elevation view thereof.

In the drawings, the broken lines shown in FIGS. 1-4 indicate portions of the article not claimed and form no part of the claimed design.

1 Claim, 4 Drawing Sheets

FIG. 1

FIG. 2

FIG. 3

FIG. 4
